C. B. WEVER.

HOLDER FOR TOOTH BRUSHES AND OTHER ARTICLES.

APPLICATION FILED MAR. 2, 1918.

1,289,025.

Patented Dec. 24, 1918.

UNITED STATES PATENT OFFICE.

CLAUDE B. WEVER, OF BROOKLYN, NEW YORK.

HOLDER FOR TOOTH-BRUSHES AND OTHER ARTICLES.

1,289,025.

Specification of Letters Patent. Patented Dec. 24, 1918.

Application filed March 2, 1918. Serial No. 220,053.

To all whom it may concern:

Be it known that I, CLAUDE B. WEVER, a citizen of the United States, and a resident of Brooklyn, in the county of Kings 5 and State of New York, have invented certain new and useful Improvements in Holders for Tooth-Brushes and other Articles, of which the following is a specification.

This invention relates to a holder of novel construction from which tooth brushes, surgical instruments and various other devices may be readily suspended by their heads in such a manner that the latter are 10 thoroughly protected against dust and other impurities. The construction of the holder is such that by pushing the article to be suspended back into the holder, the latter will be automatically closed, while by drawing 15 the article forward, the holder will be opened, so that in this way, the manipulation is greatly facilitated. The invention consists in the various features of novelty, more fully pointed out in the specification 20 and appended claims.

In the accompanying drawing:

Figure 1 is a vertical section on line 1—1 Fig. 2, of a holder embodying my invention;

Fig. 2, a horizontal section on line 2—2 30 Fig. 1, showing the holder closed;

Fig. 3, a similar section, showing the holder open;

Fig. 4, a section on line 4—4 Fig. 2;

Fig. 5, a horizontal section of a modification on line 5—5 Fig. 7, showing the holder closed;

Fig. 6, a similar section with the holder open, and

Fig. 7, a section on line 7—7 Fig. 5.

The device comprises a casing A which is closed at its back, sides, top and bottom, but is open at the front. Lugs 8 projecting from the back and apertured for the reception of nails or similar fasteners, permit the 40 casing to be attached to a wall or other support. The bottom 9 of the casing extends forwardly beyond the sides, and is provided with a centrally disposed forwardly opening slot 10. The casing is adapted to be 45 closed by a pair of vertically hung covers, each formed of a curved side or body 11, a lower inwardly extending horizontal jaw 12, and an upper inwardly extending horizontal projection or member 13. Of these 50 jaw 12 is pivotally secured to and overlies bottom 9, while projection 13 is pivotally 55 secured to and underlies the top 14 of the casing, so that the covers may be readily swung into an open or closed position. It is preferred to form the pivots by means of 60 protuberances 15, 16 struck up respectively from jaws 12 and projections 13, and engaging corresponding sockets 17, 18 formed on bottom 9 and top 14, as by this construction the covers may be readily sprung into place, 65 while all additional metal hinges or pivots are dispensed with.

Each jaw 12 is provided at its inner working edge with a straight front section 19, a notch or recess 20, back of the straight section, and a beveled section 21 back of the notch. The correlation of the parts is such, that when the covers are closed, the straight sections 19 of the two covers will become alined and abut against one another, while 70 when the covers are opened, the beveled sections 21 will become alined, and thus limit the play of the covers.

In use, the tooth brush or other article 22 to be suspended, is slipped between the open 80 jaws (Fig. 3) in such a manner that the head of the brush will project above said jaws, while the handle of the brush will be carried along slot 10 into the notches 20. By now exerting a slight pressure against 85 the handle, the latter will, by bearing against the heels 23 of notches 20, swing the jaws and consequently the entire covers into a closed position (Fig. 2), so that the casing will be closed, and the head of the 90 brush be effectively protected in a sanitary manner against germs, dust or other impurities.

To remove the brush, it is only necessary to draw the latter forward by its handle, 95 which operation will cause the jaws, and consequently the covers to open, their outward movement being limited by the beveled sections 21 coming into engagement with each other (Fig. 3).

With the embodiment shown in Figs. 5—7, the casing B has but a single cover, in lieu of the two covers illustrated in Figs. 1—4.

The bottom 24 of the casing does not protrude beyond its sides and is furnished with 105 the forwardly opening slot 25. The pivoted cover 26 has a lower jaw 27, and an upper projection 28, which are pivoted respectively to the bottom 24, and the top 29 of the casing. Jaw 27 is provided with a slot 110 or recess 30, adapted for the reception of the tooth brush handle.

When the cover is open (Fig. 6), the handle is introduced into recess 30 and by exerting a slight pressure against the handle, the cover will be swung into its 5 closed position so as to overlie bottom 24, while the handle will be simultaneously carried into the slot 25 of said bottom (Fig. 5).

To remove the tooth brush, the latter is simply drawn forward along slot 25 to press 10 against jaw 27 and thus open the cover, and return it to the position shown in Fig. 6.

It will be seen that with both embodiments, the holder is manipulated by the simple operation of pressing the brush or 15 other article either backward or forward against the jaws (or jaw) and that when housed within the casing, the head of the brush is effectively protected in a sanitary manner, while furthermore, the weight of 20 the brush is borne not only by the jaws but also by the slotted bottom, which thus serves

to prevent the latter from sagging under protracted use.

I claim:

1. A holder of the character described, 25 comprising a casing, a vertically hung cover adapted to close said casing, and a recessed jaw extending inwardly from the cover.

2. A holder of the character described, comprising a casing having a slotted bottom, a vertically hung cover adapted to close said casing, and a recessed jaw extending 30 inwardly from said cover.

3. A holder of the character described, comprising a casing having a slotted bottom, a vertically hung cover adapted to close 35 said casing, and a horizontally disposed recessed jaw extending inwardly from the lower end of said cover and adapted to overlie said slotted bottom.

CLAUDE B. WEVER.
